UNITED STATES PATENT OFFICE.

HAROLD C. SUEKERT, OF NEW YORK, N. Y.

FUEL-FEEDING DEVICE FOR INTERNAL-COMBUSTION ENGINES.

1,356,096.

Specification of Letters Patent. Patented Oct. 19, 1920.

Application filed February 3, 1919. Serial No. 274,752.

To all whom it may concern:

Be it known that I, HAROLD C. SUEKERT, a citizen of the United States, and a resident of the city, county, and State of New York, have invented certain new and useful Improvements in Fuel-Feeding Devices for Internal-Combustion Engines, of which the following is a full, clear, concise, and exact description, such as will enable others skilled in the art to which the invention relates to make and use the same, reference being made therein to the accompanying drawings, which form a part of this specification.

15 My invention relates to liquid fuel feeding devices for internal combustion engines of the type or class wherein pumping mechanism operated by gas under pressure derived from the cylinder of the engine is employed to supply liquid fuel to the carburetor or equivalent device whereby a combustible mixture for use by the engine is produced, or wherein such gas operated pumping mechanism is employed to supply 20 liquid fuel directly to the working cylinder of the engine in case no carburetor is employed; and the object thereof is to provide gas operated pumping mechanism of the type referred to and wherein means are 25 present for arresting the operation thereof when the supply of fuel to the engine or carburetor or other mixture producing device is interrupted or materially reduced in amount, as by a float controlled valve, a 30 governor, or other element provided for regulating the amount of fuel supplied to the engine; the operation of the said pumping mechanism arresting means being dependent upon the rise in pressure in the fuel 35 40 being pumped which follows the interruption or restriction of the supply thereof to the engine or to the combustible mixture producing device employed.

A further object of my invention is to 45 provide improved means for arresting the pumping action of the gas operated pumping mechanism when the flow of fuel through a conduit through which fuel for use in the engine flows therefrom is arrested in whole or to a substantial extent; 50 said means including a fuel reservoir into which the fuel is discharged by said pumping mechanism, and means the operation of which is dependent upon a rise in pres-

sure within said fuel reservoir for interrupting the operation of said pumping mechanism to supply fuel thereto.

With the above and other objects in view, my invention consists in the improved liquid fuel supply device for internal combustion engines illustrated in the accompanying drawing, described in the following specification, and particularly claimed, and in such variations and modifications thereof as will be obvious to those skilled in the art to which my invention relates.

In the drawings accompanying and forming a part of this specification and wherein the preferred embodiment of my invention is illustrated:

Figure 1 is a view showing my improved fuel supply device in section, the same being shown as employed to supply fuel to the float chamber of a carburetor whereby the engine is supplied with a combustible mixture of air and a hydrocarbon;

Fig. 2 is a view showing a section upon a transverse plane indicated by the line 2—2, Fig. 1;

Fig. 3 is a sectional view similar to Fig. 1 but showing a modified form of pumping mechanism, the device whereby the fuel pumped by said mechanism is supplied to the engine cylinder not being illustrated, and

Figs. 4, 5, and 6 are views similar to Fig. 3 but showing modifications.

Referring now to the drawings the reference numeral 5, Fig. 1, designates the cylinder of an internal combustion engine, 6 the piston thereof, and 7 a normally open outlet passage through which gas under pressure may flow from the interior of the cylinder through a conduit 8 to my improved fuel feeding device; such flow or at least the greater part thereof occurring near the end of the compression stroke and early in the working stroke of the piston of the engine when the pressure within the cylinder is the highest, as will be understood. 100 The outlet from the cylinder is permanently open so that gas may flow from the interior of the cylinder whenever the pressure therein is sufficiently high, although a needle valve 9 is preferably provided in order to regulate the flow of gas from the engine cylinder.

The mechanism immediately concerned

with the feeding of the fuel in my improved fuel feeding device or system includes a closed fuel reservoir 11 which may be provided by a casing of any suitable form, but 5 which casing is shown as comprising a cylindrical shell 12 one end of which is closed by a head 13 having a peripheral flange 14, whereby the casing may be secured to a suitable support; and the other end of which 10 shell is closed by a yieldable diaphragm 15 which forms a part of the wall of the casing; the said diaphragm being held in place against a circumferentially extending shoulder or ledge 16 by means of a head 17 shown 15 as having one or more openings 18, so that one side of the diaphragm is always exposed to the pressure of the atmosphere while the other side thereof is exposed to the pressure within the fuel reservoir. 20 Associated with the fuel reservoir aforesaid and shown as extending through or across the casing 12 is a tube 19, the ends of which are secured in oppositely located openings in the wall thereof, and which tube 25 forms a permanent part of and is permanently secured in place relative to the casing. The upper end of this tube is closed by a head 20 in threaded engagement therewith, and this head supports a cylinder 21 30 depending into the tube 19; so that the cylinder may be defined as supported by or from the casing and located within or extending thereinto, although a small part of the interior of the cylinder is in fact within 35 the head 20 in the embodiment of my invention illustrated in Fig. 1. The open lower end of the cylinder is closed by a head 22 having a depending pipe 23 of less diameter than and which extends to the lower head 40 24 of the tube 19, and there communicates with the discharge end of an inlet conduit 25 connected with said head, and which conduit leads from a suitable fuel storage tank not shown. 45 The lower end of the cylinder 21 is provided with a flange 26 the periphery of which forms a tight fit with the inner surface of the tube 19, whereby a leak chamber 27 is provided between the said cylinder 50 and the tube 19 the upper end of which is in communication with the atmosphere through a passage 28 in the head 20, and one or more holes 29 are provided in the wall of said cylinder through which any gas 55 which may leak past the piston 38 may escape into the chamber 27 and pass to the external atmosphere.

The concentric arrangement of the tube 19 and the pipe 23, and the fact that the 60 lower end of said pipe forms a tight joint or connection, as by means of a conical joint at 30, with the end of the fuel supply conduit 25, provides an intermediate trap chamber 31 into which the fuel is forced from 65 the cylinder 21 through discharge passages

32 in the head 22, and past an annular spring closed discharge valve 33 seating upon the under side of said head.

The purpose of the trap chamber 31 is to arrest the flow of such water or sediment as 70 may be carried along by the stream of fuel flowing from the pump cylinder through the discharge passage leading therefrom to the fuel reservoir 11; it being obvious that such sediment and water as may be entrained in the stream of fuel will collect 75 within the said chamber, instead of passing into the fuel reservoir along with the fuel and therefrom to the engine.

The flow of fuel through the fuel supply 80 conduit provided by the conduit 25 and the pipe 23 into the cylinder 21 takes place past an inlet supply check valve 34, and the fuel discharged into the trap chamber 31 as aforesaid flows therefrom and into the fuel 85 reservoir 11 through a normally open discharge passage 35. This passage, however, is adapted to be closed to thereby prevent a further flow of fuel into the fuel reservoir by a spring operated valve 36, which valve 90 is controlled by and held off its seat 37 by the yieldable diaphragm 15; but which valve will close onto its seat 37 and interrupt the flow of fuel through the discharge 95 passage aforesaid when the diaphragm moves to the right, Fig. 1, due to a rise of pressure within the fuel reservoir.

The inner surface or wall of the cylinder 21 as hereinbefore explained is shown as extending into the head 20, and the reference 100 numeral 38 designates a cup-shaped piston operating within the said cylinder and whereby a motor chamber 39 is provided at the upper end of the said cylinder, and a pumping chamber 40 at the lower end thereof. A spring 42 operates between the head 22 and the closed upper end of the piston 38 and acts to force said piston upward, or toward the motor chamber 39, and gas under pressure flowing through the gas pressure supply conduit 8 flows into and out from the motor chamber 39 through a passage 41 in the head 20; thereby operating the gas operated pumping mechanism provided by the cylinder and piston, and the 115 valve controlled inlet and outlet passages associated with the pump chamber 40, as will be appreciated.

The diaphragm 15 acts to hold the valve 36 in the normal open position in which it is 120 shown to which end said valve is provided with a stem 43, the extremity of which is in operative engagement with a plug 44 carried by a bushing 45 held in place in an opening provided in the diaphragm; and movement of the diaphragm in a direction 125 to permit the valve 36 to close, that is to the right in Fig. 1, is opposed by a spring 46 the opposing force of which may be regulated by a hollow plug 47 in threaded en- 130

gagement with the head 17 of the casing which forms the fuel reservoir.

An outlet conduit 48 leads from the fuel reservoir 11 to the carbureter or equivalent device whereby fuel is supplied to the engine. In the embodiment of my invention illustrated the fuel supplying device is in the form of a carbureter whereby a combustible mixture of air and liquid fuel for use by the engine is formed, and which mixture flows to the engine through a mixture supply conduit 49. The said carbureter is shown as having a fuel reservoir 50 within which a substantially uniform level of fuel is maintained as by a float 51 located therein, and which float closes a valve 52 with which it is operatively connected whenever the fuel rises above a predetermined level in the reservoir 50, thus arresting the flow of fuel through the conduit 48 and into the fuel reservoir 50, as will be understood.

In view of the premises it will be appreciated that the head 20 may be unscrewed from the upper end of the tube 19, which is ordinarily permanently secured in place in the walls 12 of the fuel reservoir 11; and the cylinder 21 carried by said head, the head 22 at the lower end of said cylinder together with the inlet and discharge valves of the pumping chamber 40, and the depending fuel inlet pipe 23 all removed from the tube 19 as a single unitary structure; thus providing a construction in which the greater part of the operating elements of the device may be assembled as a unitary structure or mechanism apart from the other elements thereof, and then readily placed in operative relation with such other elements; and as readily removed from the tube in which they are located for inspection, re-adjustment or repair, should such a course be necessary or desirable.

The operation of the form of my invention illustrated in Fig. 1 is substantially as follows: When the engine with which the device is used is in operation gas under pressure will flow from the cylinder 5 through the gas pressure supply conduit 8 and into the motor chamber 39 of the cylinder 21, thus forcing the piston 38 downward against the action of the spring 41; the resistance of the said spring being such that the high pressure present in the cylinder at or about the end of the compression stroke, or during the greater part of the working stroke, is necessary to produce downward movement of the pumping piston 38, the said spring acting to return the pumping piston into its uppermost position and produce a flow of gas along the conduit 8 toward the engine cylinder when the pressure therein is low, as during the exhaust, suction, and throughout the greater part if not all of the compression strokes of the engine piston.

The reciprocating movement thus imparted to the piston 38 induces a flow of liquid fuel into the pumping chamber 40 through the fuel supply conduit 25 and the pipe 23, and past the inlet valve 34; which fuel is forced from the said pumping chamber past the outlet valve 33 into the trap chamber 31, and from said chamber through the passage 35 and past the normally open valve 36 and into the fuel reservoir 11. 75

The liquid fuel will be forced into the fuel reservoir 11 against the back pressure of whatever air or gas may be present therein, and the level of the fuel within said reservoir will obviously depend upon the vertical position or location of said reservoir relative to the carbureter or other fuel supplying device to which the liquid fuel is supplied through the fuel outlet conduit 48 leading thereto; the preferred arrangement 80 of the fuel reservoir and the device which is supplied with fuel therefrom being such that the pressure within the said reservoir will be sufficient to produce a supply of fuel under pressure to the device which supplies 85 fuel to the engine, in order to insure a prompt and adequate supply of fuel for the needs of the engine with which the device is used. 90

The operation above explained will continue as long as the engine remains in operation, and until the flow of liquid fuel through the outlet conduit 48 is arrested or substantially reduced in amount by the closing of the valve 52, or otherwise in 95 other forms of device for supplying fuel to the engine. When, however, the flow of fuel along the said conduit is arrested or materially restricted the pressure within the fuel reservoir 11 will rise, the diaphragm 15 will 100 be forced to the right against the action of the spring 46, and the normally open valve 36 will be permitted to close onto its seat, thus interrupting the flow of fuel along the passage 35 and into the fuel reservoir; the valve 36 and the yieldable diaphragm thus 105 providing means the operation of which is dependent upon a rise of pressure within the fuel reservoir for limiting the rise of pressure which would occur therein when the 110 flow of fuel through the outlet conduit 48 is interrupted or reduced to an extent sufficient to bring about the closing of the said valve, should the pumping mechanism continue to operate after the flow through said 115 conduit 48 is reduced or arrested as aforesaid. The liquid thus trapped within the trap chamber 31 and the pumping chamber 40 will prevent downward movement of the piston 38, thus suspending the supply of 120 fuel to the fuel reservoir 11. 125

It will be appreciated that although the rise in pressure within the fuel reservoir is limited in the manner above explained the operation above outlined will build up a 130

pressure within the fuel reservoir 11, somewhat higher than the pressure normally present therein, as the pressure must increase in order to bring about the operation 5 of the means which prevents a further increase in pressure; so that a prompt and vigorous flow of liquid fuel will occur through the fuel supply conduit 48 immediately upon the opening of the valve 52, or 10 upon an opening movement of whatever device may be employed for controlling the flow of liquid fuel through the fuel supply conduit 48.

The degree or extent of the rise in pressure which occurs within the fuel reservoir 15 when the flow through the outlet conduit is interrupted is regulated by the spring 46 and cup 47 in engagement therewith; it being obvious that the greater the resistance 20 of the spring the greater will be the rise in pressure within the fuel reservoir necessary to move the diaphragm away from the stem of the valve 36, so that the said valve may move into engagement with its seat and thus 25 arrest the flow of fuel into the fuel reservoir.

In the modified form of my invention illustrated in Fig. 3 the piston 53 operates in a cylinder 54 located within a fuel reservoir 55 having a diaphragm 56 substantially as in the form of my invention illustrated in Fig. 1; the piston being forced upward by a spring 57, the liquid fuel entering the pumping chamber 58 through a passage 59 having a check valve 60, and the same passing from the pumping chamber through a passage 61 controlled by a spring closed check valve 62. The flow of fuel into the pumping chamber takes place past a normally open valve 63 urged toward its seat by a spring 64, but which valve is prevented from moving onto its seat by a bent lever 65 supported by a ball and socket or equivalent pivotal support, as shown at 66; the 40 lower end of said lever being operatively connected with the valve 63 in any way as by a rounded head at the end thereof which enters a slot provided in the valve, while the upper end of said lever is pressed against 45 the diaphragm 56 by the spring 64.

When now the flow of fuel through the outlet conduit 48 is arrested or restricted the resulting rise of pressure within the reservoir 55 will move the diaphragm 56 to 55 the right and permit the spring 64 to close the valve 63, thus arresting the supply of fuel to the pumping chamber and of course preventing a further supply of fuel to the fuel reservoir, the same as in the form of 60 my invention illustrated in Fig. 1 so far as concerns the ultimate end or result secured.

In this form of my invention a tube 67 is carried by the lower head of the cylinder 54, and a buffer 68 is located at the upper 65 end of said tube and is pressed upward by

a spring 69 housed within the tube. The piston 53 is provided with a depending wall 70 which engages the buffer 68 and cushions the piston at the end of the downward movement thereof, this being desirable especially when the valve 63 prevents the entry of fuel into the pumping chamber for any considerable number of strokes of the piston 53, as may occur when the device is in use. 75

In the embodiment of my invention illustrated in Fig. 4 the piston 71 moving within the cylinder 72 draws liquid fuel into the pumping chamber 73 through the passage 74 and past the check valve 75 upon 80 its up stroke caused by the spring 76, and forces such fuel past the check valve 77 and into the fuel reservoir 78 upon its down stroke, as will be appreciated.

In this form of my device a bypass passage 79 communicates with the passage 74 below the valve 75, the outlet end of the said passage being normally closed by a valve 80 held against its seat by a spring 81, or by said spring acting in conjunction with 90 the diaphragm 82; from which it follows that a rise in pressure within the fuel reservoir will open the valve 80 and permit fuel to flow from the said reservoir through the by-pass passage 79 and back to the inlet 95 passage 74, thus preventing a further rise of pressure within the fuel reservoir, when the flow through the outlet conduit 48 is arrested or materially reduced in quantity.

In the forms of my invention hereinbefore explained the gas flowing to the pumping mechanism will act upon the upper end of the motor and pumping piston even though no fuel is being forced into the fuel reservoir. Fig. 5, however, illustrates a 100 form of my invention in which the pressure within the motor chamber 83 is prevented from rising and thus subjecting the piston to pressure when the discharge of fuel from the fuel reservoir is arrested under 105 the conditions hereinbefore explained; this end being accomplished by the use of a by-pass passage 84 leading from the motor chamber and the flow of gas through which is normally prevented by an adjustable 110 spring pressed and normally closed valve 85 the stem of which may be engaged by the diaphragm 86.

When the pressure within the fuel reservoir rises the diaphragm 86 will be forced 115 to the right, the valve 85 will be opened, and a free communication will be established from the motor chamber 83 to the external atmosphere through the by-pass 84 and the holes 18; thus suspending the operation of 120 the pumping mechanism and interrupting the supply of fuel to the fuel reservoir, as 125 will be appreciated.

Fig. 6 illustrates a form of my invention in which the area of the motor chamber 87 130

is greater than that of the pumping chamber 88; the combined motor and pumping piston having a larger head 89 operating in a cylinder 90, and a plunger 91 operating in a cylinder 92 of reduced diameter. The combined piston is forced upward by a spring 93 surrounding the plunger 91 and is therefore out of contact with the liquid fuel being pumped, and such gas as may 10 leak past the piston head 89 passes to the atmosphere through holes 94.

In this form of my invention the fuel passes into the pumping chamber 88 through a fuel supply passage 95 and past a check 15 valve 96, and is forced therefrom past an outlet valve 97 and into the fuel reservoir 98 and, while the action of the pump to supply fuel to the fuel reservoir upon the happening of the events hereinbefore explained 20 may be suspended in any of the ways hereinbefore pointed out at length, the drawing shows a by-pass passage 99 leading from the motor chamber 87 and through which gas may escape to the atmosphere upon a rise 25 in pressure within the fuel reservoir 98; said by-pass being of the same kind, and controlled in the same way as the by-pass 84 employed in the form of my invention illustrated in Fig. 5, and hereinbefore described.

Reference is hereby made to my copending applications, Ser. Nos. 268,006, 335,648, 389,722 and 389,723, which include the subject matter disclosed, but not claimed herein.

Having thus described and explained my invention, I claim and desire to secure by Letters Patent:

1. In a fuel feeding device of the class described, gas operated pumping mechanism; a closed fuel reservoir; a valve controlled fuel supply conduit through which fuel is supplied to said pumping mechanism; a valve controlled discharge passage leading from said pumping mechanism to 40 said fuel reservoir; an outlet conduit leading from said fuel reservoir; and means the operation of which is dependent upon an increase in pressure within said fuel reservoir for limiting the rise in pressure therein 45 for following an interruption of the flow of fuel through said outlet conduit.

2. In a fuel feeding device of the class described, gas operated pumping mechanism; a permanently open gas supply conduit through which gas may flow to and from said pumping mechanism to operate the same; a closed fuel reservoir; a valve controlled fuel supply conduit through which fuel is supplied to said pumping mechanism; a valve controlled discharge passage leading from said pumping mechanism to 55 said fuel reservoir; an outlet conduit leading from said fuel reservoir and adapted to deliver fuel against varying pressure; and means the operation of which is dependent

upon an increase in pressure within said fuel reservoir for limiting the rise in pressure therein which follows interruption of the flow of fuel through said outlet conduit.

3. In a fuel feeding device of the class described, gas operated pumping mechanism; a closed fuel reservoir; a valve controlled fuel supply conduit through which fuel is supplied to said pumping mechanism; a valve controlled discharge passage leading 70 from said pumping mechanism to said fuel reservoir; an outlet conduit leading from said fuel reservoir and adapted to deliver fuel against varying pressure; and means the operation of which is dependent upon 80 an increase in pressure within said fuel reservoir for interrupting the operation of said pumping mechanism to increase the amount of fuel within said fuel reservoir, when the flow of fuel through said outlet 85 conduit is arrested.

4. In a fuel feeding device of the class described, gas operated pumping mechanism; a closed fuel reservoir; a valve controlled fuel supply conduit through which fuel is supplied to said pumping mechanism; a valve controlled discharge passage leading 90 from said pumping mechanism to said fuel reservoir; an outlet conduit leading from said fuel reservoir and adapted to deliver 95 fuel against varying pressure; and pressure operated means for limiting the rise of pressure within said fuel reservoir which follows arresting the flow of fuel through said outlet conduit.

5. In a fuel feeding device of the class described, gas operated pumping mechanism; a closed fuel reservoir; a valve controlled fuel supply conduit through which fuel is supplied to said pumping mechanism; a valve controlled discharge passage leading 105 from said pumping mechanism to said fuel reservoir; an outlet conduit leading from said fuel reservoir and adapted to deliver fuel against retarding pressure; and pressure operated means for interrupting the operation of said pumping mechanism to increase the amount of fuel within said fuel reservoir, when the flow of fuel through 110 said outlet conduit is retarded.

6. In a fuel feeding device of the class described, gas operated pumping mechanism; a closed fuel reservoir; a valve controlled fuel supply conduit for supplying fuel to said pumping mechanism; a valve controlled discharge passage leading from said pumping mechanism to 120 said fuel reservoir; an outlet conduit leading from said fuel reservoir and adapted to deliver fuel against retarding pressure; and pressure operated means for limiting the pressure within said fuel reservoir.

7. In a fuel feeding device of the class described, a cylinder; a piston operating with 125 in said cylinder and whereby a motor cham-

100

115

120

125

130

ber is provided at one end and a pump chamber at the other end thereof; a permanently open gas supply conduit through which gas may flow to and from said motor chamber; a spring for moving said piston toward said motor chamber; a closed fuel reservoir; a valve controlled fuel supply conduit for supplying fuel to said pump chamber; a valve controlled discharge passage 5 leading from said pump chamber to said fuel reservoir; an outlet conduit leading from said fuel reservoir and adapted to be subjected to pressure retarding the passage of fuel therethrough; and pressure operated 10 means for limiting the pressure within said fuel reservoir.

8. In a fuel feeding device of the class described, a cylinder; a piston operating within said cylinder and whereby a motor chamber is provided at one end and a pump chamber at the other end thereof; a permanently open gas supply conduit through which gas may flow to and from said motor chamber; a spring for moving 15 said piston toward said motor chamber; a closed fuel reservoir; a valve controlled fuel supply conduit for supplying fuel to said pump chamber; a valve controlled discharge passage leading from said pump chamber to said fuel reservoir; an outlet conduit leading 20 from said fuel reservoir; means for arresting the flow of fuel through said outlet conduit; a yieldable diaphragm exposed to the pressure within said fuel reservoir; and a normally open valve controlled by said diaphragm and adapted to arrest the flow 25 of fuel from said pump chamber through the discharge passage aforesaid and into said fuel reservoir upon a rise of pressure within 30 said reservoir.

9. In a fuel feeding device, a closed fuel 35 reservoir adapted to contain a substantial quantity of liquid fuel with an air space thereover, a pump for supplying fuel to said reservoir, a fuel outlet conduit leading from said reservoir and adapted to be subjected 40 to pressure retarding the delivery of fuel, and means operated by rise of pressure within the reservoir for limiting the rise of pressure therein which follows retardation of the flow of fuel through the outlet 45 conduit, whereby the pressure within the reservoir may be kept within safe limits.

10. In a fuel feeding device of the class described; a cylinder; a piston operating within said cylinder and whereby a motor 50 chamber is provided at one end and a pump chamber at the other end thereof; a permanently open gas supply conduit through which gas may flow to and from said motor chamber; a spring for moving said piston 55 toward said motor chamber; a closed fuel reservoir; a valve controlled fuel supply conduit for supplying fuel to said pump chamber; a valve controlled discharge passage 60 leading from said pump chamber to said fuel reservoir; a valve controlled discharge passage leading from said pump chamber to

said fuel reservoir; an outlet conduit leading 65 from said fuel reservoir; means for controlling the flow of fuel through said outlet conduit; a yieldable diaphragm operated by the pressure within said fuel reservoir; and a valve controlled by said diaphragm and adapted to prevent a further supply of fuel to said fuel reservoir when the flow of fuel through said outlet conduit is interrupted.

11. In a fuel feeding device of the class 70 described, a cylinder; a piston operating within said cylinder and whereby a motor chamber is provided at one end and a pump chamber at the other end thereof; a permanently open gas supply conduit through 75 which gas may flow to and from said motor chamber; a spring for moving said piston toward said motor chamber; a closed fuel reservoir; a valve controlled fuel supply conduit for supplying fuel to said pump chamber; a valve controlled discharge passage 80 leading from said pump chamber to said fuel reservoir; an outlet conduit leading from said fuel reservoir; means for arresting the flow of fuel through said outlet 85 conduit; a yieldable diaphragm exposed to the pressure within said fuel reservoir; and a normally open valve controlled by said diaphragm and adapted to arrest the flow 90 of fuel from said pump chamber through the discharge passage aforesaid and into said fuel reservoir upon a rise of pressure within 95 said reservoir.

12. In a fuel feeding device of the class 100 described, a cylinder; a piston operating within said cylinder and whereby a motor chamber is provided at one end and a pump chamber at the other end thereof; a permanently open gas supply conduit through 105 which gas may flow to and from said motor chamber; a spring for moving said piston toward said motor chamber; a closed fuel reservoir; a valve controlled fuel supply conduit for supplying fuel to said pump chamber; a valve controlled discharge passage 110 leading from said pump chamber to said fuel reservoir; an outlet conduit leading from said fuel reservoir; means for arresting the flow of fuel through said outlet conduit; a yieldable diaphragm exposed to 115 the pressure within said fuel reservoir; a valve normally held away from its seat by said diaphragm, and which valve is adapted to arrest the flow of fuel from said pump chamber through the discharge passage 120 aforesaid and into said fuel reservoir; and a spring for closing said valve onto its seat upon a movement of said diaphragm away therefrom, due to a rise of pressure within 125 said fuel reservoir.

13. In a fuel feeding device of the class described, a closed casing whereby a fuel reservoir is provided and the wall of which

- is formed in part by a yieldable diaphragm; a cylinder supported by said casing and extending thereinto; a piston operating within said cylinder and whereby a motor 5 chamber is provided at one end and a pump chamber at the other end thereof; a gas supply conduit through which gas may flow into and out from said motor chamber; a spring for moving said piston toward said 10 motor chamber; a valve controlled fuel supply conduit for supplying fuel to said pump chamber; a valve controlled passage leading from said pump chamber to said fuel reservoir and discharging thereinto; an outlet conduit leading from said fuel reservoir; means for controlling the flow of fuel through said outlet conduit; and means operated by said diaphragm for limiting the 15 pressure within said fuel reservoir.
14. In a fuel feeding device of the class described, a closed casing whereby a fuel reservoir is provided and the wall of which is formed in part by a yieldable diaphragm; a cylinder supported by said casing and extending thereinto; a piston operating within said cylinder and whereby a motor chamber is provided at one end and a pump chamber at the other end thereof; a gas 20 supply conduit through which gas may flow into and out from said motor chamber; a spring for moving said piston toward said motor chamber; a valve controlled fuel supply passage through which fuel is supplied to said pump chamber; a valve controlled passage leading from said pump chamber to said fuel reservoir and discharging thereinto; an outlet conduit leading from said fuel reservoir; and a normally open valve controlled by said diaphragm and adapted to arrest the flow of fuel 25 into said fuel reservoir upon a rise of pressure therein.
15. In a fuel feeding device of the class described, a closed casing whereby a fuel reservoir is provided and the wall of which is formed in part by a yieldable diaphragm; a cylinder supported by said casing and extending thereinto; a piston operating within said cylinder and whereby a motor chamber is provided at one end and a pump chamber at the other end thereof; a gas supply conduit through which gas may flow into and out from said motor chamber; a valve controlled fuel supply passage leading from said pump chamber to said fuel reservoir and discharging thereinto; an outlet conduit leading from said fuel reservoir; means for arresting the flow of fuel through said outlet conduit; and means 30 operated by said diaphragm for preventing a further supply of fuel to said fuel reservoir when the pressure therein rises to a predetermined amount.
16. In a fuel feeding device of the class described, a closed casing whereby a fuel reservoir is provided and the wall of which is formed in part by a yieldable diaphragm; a cylinder supported by said casing and extending thereinto; a piston operating within said cylinder and whereby a motor chamber is provided at one end and a pump chamber at the other end thereof; a gas supply conduit through which gas may flow into and out from said motor chamber; a spring for moving said piston toward said motor chamber; a valve controlled fuel supply conduit for supplying fuel to said pump chamber; a valve controlled passage leading from said pump chamber to said fuel reservoir and discharging thereinto; an outlet conduit leading from said fuel reservoir; means for arresting the flow of fuel through said outlet conduit; and a normally open valve controlled by said diaphragm and adapted 40 to arrest the flow of fuel from said pump chamber through the discharge passage aforesaid and into said fuel reservoir upon a rise of pressure within said reservoir.
17. In a fuel feeding device of the class described, a closed casing whereby a fuel reservoir is provided; a tube secured in place within said casing; an inlet conduit connected with said tube; a removable cylinder secured in place within said tube and having a pipe smaller in diameter than said tube, and the end of which pipe forms a tight joint with the discharge end of said inlet conduit; whereby a trap chamber is provided between said pipe and the interior of said tube; a piston operating within said cylinder and whereby a motor chamber is provided at one end and a pump chamber at the other end thereof; a valve for controlling the supply of fuel through said pipe and into said pump chamber; a valve controlled discharge passage leading from said pump chamber into said trap chamber; and a passage leading from said trap chamber into said fuel reservoir.
18. In a fuel feeding device of the class described, a closed casing whereby a fuel reservoir is provided and the wall of which is formed in part by a yieldable diaphragm; a tube secured in place in oppositely located openings provided in the wall of said casing; an inlet conduit connected with the lower end of said tube; a removable cylinder secured in place in the upper portion of said tube and having a pipe smaller in diameter than said tube, and the lower end of which pipe forms a tight joint with the discharge end of said inlet conduit, whereby a trap chamber is provided between said pipe and the interior of said tube; a piston operating 50

- within said cylinder and whereby a motor chamber is provided in the upper end and a pump chamber at the lower end thereof; a spring for moving said piston toward said 5 motor chamber; a valve for controlling the supply of fuel through said pipe and into said pump chamber; a valve controlled discharge passage leading from said pump chamber into said trap chamber; a passage 10 leading from said trap chamber into said fuel reservoir; and a normally open valve controlled by said diaphragm for interrupting the flow of fuel into said fuel reservoir upon a rise of pressure therein.
- 15 19. In a fuel feeding device of the class described, a closed casing whereby a fuel reservoir is provided and the wall of which is formed in part by a yieldable diaphragm; a tube secured in place in oppositely located 20 openings provided in the wall of said casing; an inlet conduit connected with the lower end of said tube; a removable cylinder secured in place in the upper portion of said tube and having a pipe smaller in diameter 25 than said tube, and the lower end of which pipe forms a tight joint with the discharge end of said inlet conduit, whereby a trap chamber is provided between said pipe and the interior of said tube; a piston 30 operating within said cylinder and whereby a motor chamber is provided in the upper end and a pump chamber at the lower end thereof; a spring for moving said piston toward said motor chamber; a valve for controlling the supply of fuel through said 35 pipe and into said pump chamber; a valve controlled discharge passage leading from said pump chamber into said trap chamber; a passage leading from said trap chamber into 40 said fuel reservoir; a valve normally held away from its seat by said diaphragm, and which valve is adapted to arrest the flow of fuel into said fuel reservoir upon a rise of pressure therein; and a spring for closing said valve onto its seat upon movement of said diaphragm away therefrom, due to a rise of pressure within said fuel reservoir. 45
20. In a fuel feeding device of the class described; a closed casing whereby a fuel reservoir is provided; a tube secured in place within said casing; an inlet conduit connected with the lower end of said tube; a removable cylinder smaller in diameter than said tube and secured in place in the 50 upper portion thereof, and having a flange at its lower end contacting with the interior of the tube, to thereby provide a leak chamber between said cylinder and tube, said cylinder having also a depending pipe 55 smaller in diameter than said tube and the lower end of which pipe forms a tight joint with the discharge end of said inlet conduit whereby a trap chamber is provided between said pipe and the interior of said tube; a piston 60 operating within said cylinder and whereby a motor chamber is provided at the upper end and a pump chamber at the lower end thereof; a valve for controlling the supply of fuel through said pipe and into said pump chamber; a valve controlled discharge passage leading from said pump chamber into said trap chamber; and a passage leading from said trap chamber into 65 said fuel reservoir. 70
- 75 In testimony whereof, I have signed my name to this specification this 30th day of January 1919.

HAROLD C. SUEKERT.
